UNITED STATES PATENT OFFICE.

WILLIAM J. COOK, OF CHARLOTTE, NORTH CAROLINA.

PUSH-BUTTON.

1,245,570.

Specification of Letters Patent.

Patented Nov. 6, 1917.

Application filed June 26, 1916. Serial No. 105,921.

To all whom it may concern:

Be it known that I, WILLIAM J. COOK, a citizen of the United States, residing at Charlotte, in the county of Mecklenburg and State of North Carolina, have invented 5 certain new and useful Improvements in Push-Buttons, of which the following is a specification.

This invention relates to circuit closers 10 commonly known as push buttons, and one object is to provide an improved construction in which sticking or jamming of the parts is impossible.

Another object is to provide an improved 15 construction of contact whereby different faces thereof may be engaged by the circuit closing element. Further objects and advantages will appear from the following description, taken in connection with the accompanying drawings in which,

Figure 1 is a sectional elevation, showing my improved push buttons as they appear when mounted for use, as, for example, in an elevator;

Fig. 2 is a front view of the parts shown in Fig. 1;

Fig. 3 is a front view, and Fig. 4 a sectional elevation showing a slightly modified form of push button which I employ 30 when the same is to be mounted in a wall or the like;

Fig. 5 is a side elevation of one of my improved push buttons;

Fig. 6 is a central, longitudinal section 35 thereof, parts being in elevation;

Fig. 7 is an inverted plan view thereof; and,

Fig. 8 is a perspective view of one of the contact members.

Referring to the drawings in detail, my 40 improved push button or circuit closer comprises a base 1, circular in form and composed of some insulating material. This base is provided on one side with a central projecting boss 2, which is provided with screw-threads over which engages the internally threaded end of a cylindrical barrel 3. This barrel may preferably be formed of metal, such as brass. At the open 45 end of the barrel 3 is formed an internally projecting, annular flange 4, against the inside of which engages a flange 5, formed at the inner end of a push button 5. This button 5 projects considerably beyond the 50 end of the barrel, as shown. Within the barrel 55 and disposed adjacent

the inner face of the button 5 is arranged the flat head 6 of a plunger 7. This plunger is surrounded by a light helical spring 8, bearing at one end against the head 6, 60 and at its other end against inwardly projecting lugs 9^a, carried by a tube 9, fitting within a bore in the boss 2. This tube is supported and prevented from inward longitudinal movement by means of lugs 10, 65 carried by the boss 2.

To the inner end of the plunger 7 is secured a block 11, as by means of screw threads 12. These threads permit of the total length of the plunger being adjusted 70 as desired.

Secured to the lower flat face of the base 1 is a pair of angle brackets 13, spaced apart and attached by means of screws 15. A contact member or anvil 14 is carried by 75 each bracket 13, such contact members projecting toward each other and spaced slightly apart. They are disposed accurately in alinement and so arranged as to be bridged by the block 11 when the plunger 80 is depressed.

Referring to Fig. 8, it will be seen that each contact member 14 comprises a square head having flat faces, and a screw-threaded shank 14^a. This shank projects through 85 an opening in the bracket 13, and the wire 16 forming the circuit to be closed is looped around this shank. A nut 17 is then screwed up against the wire so as to hold it in place, and a second or lock nut 18 is preferably 90 superposed upon the nut 17, so as to prevent accidental loosening.

As above stated, each contact member has a square head provided with four flat faces, and it is evident that by loosening the nuts 95 17 and 18, any desired one of these faces may be turned into position to be engaged by the block 11. Thus, if one face becomes corroded or oxidized, a new face can be readily turned into position. These faces being 100 smooth and flat, afford a broad contact surface and insure ample current carrying capacity.

The upper end of the barrel 3 is preferably threaded, and a similarly threaded 105 washer or face plate 19 is provided and arranged to screw over the same.

Referring to Figs. 1 and 2, a pair of buttons A and B are shown mounted in a pair of blocks Y-Z, clamped together around a 110 part X of an elevator frame or the like, the blocks being held together by means of suit-

able screws 20. It will be understood that in assembling these parts, the face plate 19 is removed and the casing 3 inserted from the back side into a suitable opening in the block Y, whereupon the face plate 19 is screwed down tight, thus firmly holding the button in position.

When, however, it is desired to mount a button in a socket in a wall, or the like, 10 where the rear side is not accessible, a face plate 19', larger than the base 1, is provided so as to cover the mouth of the opening or socket, as clearly shown in Figs. 3 and 4. In this case, the face plate may be secured in 15 position by means of small screws 21.

It will be seen that the button 5, when depressed, engages the flat head 6 of the plunger and forces the block 11 against the anvils 14 with a firm pressure. It will also 20 be apparent that when released the spring 8 positively returns the parts to their normal position, and that there is nothing which can possibly stick or become jammed.

What I claim is:

25 1. A circuit closer comprising a cylindrical barrel, a base larger than the barrel, a tube or socket mounted in said base within and centrally of said barrel, a plunger extending through said tube and having a flat 30 head and shank, a helical spring surround-

ing said plunger below the head and seated within said tube, a removable face plate secured to the end of the barrel opposite said base and projecting beyond the barrel to form an annular flange, a button extending 35 through said face plate and having a flat inner face arranged to engage the flat head of said plunger, said button being separate from and unconnected with said plunger, a contact block adjustably secured to the inner end of said plunger and projecting through said base, and a pair of spaced contacts carried by said base outside of said barrel adapted to be engaged by said contact block when the plunger is actuated. 40 45

2. A circuit closer comprising a suitable base having an opening, a spring pressed plunger working through said opening, and a pair of spaced, alined contacts mounted on said base adjacent the opening and adapted 50 to be bridged by said plunger, each of said contacts comprising a rotatable anvil having a plurality of flat faces disposed around the axis of rotation and extending parallel with such axis, anyone of which faces may be 55 brought into position to be engaged by said plunger.

In testimony whereof I have affixed my signature.

WILLIAM J. COOK.
